(57) CLAIM

I claim the ornamental design for a spa jet design, as shown and described.

DESCRIPTION

FIG. 1 is a front elevation view of the spa jet design showing my new design;

FIG. 2 is a rear elevation view thereof;

FIG. 3 is a right side elevation view thereof, the left side, top and bottom are identical;

FIG. 4 is a front perspective view thereof; and,

FIG. 5 is a rear perspective view thereof.

The broken lines depicting internal surfaces of the spa jet in FIG. 1 and FIG. 4 are for illustrative purposes only and form no part of the claimed design.
